UNITED STATES PATENT OFFICE.

JOSEPH KRAKER, OF SAN FRANCISCO, CALIFORNIA, ASSIGNOR, BY DIRECT AND MESNE ASSIGNMENTS, TO THE FAULTLESS GAS SAVER COMPANY, OF SAME PLACE.

INDEPENDENT GAS-BURNER REGULATOR.

SPECIFICATION forming part of Letters Patent No. 537,294, dated April 9, 1895.

Application filed August 3, 1894. Serial No. 519,360. (No model.)

To all whom it may concern:

Be it known that I, JOSEPH KRAKER, a citizen of the United States, residing in the city and county of San Francisco, State of California, have invented an Improvement in Independent Gas-Burner Regulators; and I hereby declare the following to be a full, clear, and exact description of the same.

My invention relates to a device for regulating the flow and pressure of gas.

It consists in a device attachable to each burner independently, and in certain details of construction which will be more fully explained by reference to the accompanying drawings, in which—

Figure 1 is a vertical section. Fig. 2 is a perspective view of the valve seat.

The object of my invention is to provide a device for regulating the flow of gas through each burner independently, so that whatever the size of the burner, a certain consumption of gas within the capacity of the burner may be assured.

A is a casing of sufficient size to contain the valve B and the valve seat C. This casing has its lower end so constructed as to be properly secured to the upper end of the supply pipe D through which the gas arrives at the burner.

From the top of the case is a tubular extension E having its exterior and interior screw-threaded. Upon the exterior of this extension the gas burner tube F is screwed so that there is a tight joint between the supply pipe D and the burner tip, the gas being all delivered into the interior of the casing A.

The valve seat C is shown in the form of a hollow cone having a screw-threaded hollow extension C' which is adapted to screw into the inner threads of the extension E at the top of the case A, so that the valve seat will be situated a short distance above the open end of the pipe D, and the openings through which the gas flows into the case A.

The valve B is a light conical shell of similar shape to the valve seat C and adapted to fit within it when closed. This valve has a stem G which extends up within the hollow extension C' of the valve seat, and also down through a hole made in the part into which

the pipe D is secured so that the stem is suitably guided, and the valve allowed to rise and fall at will.

The interior of the valve seat C has grooves H made in it extending from the bottom up 55 to a point where they connect with the interior passage, for the purpose of allowing a small flow of gas when the valve has been closed.

The valve B is so arranged with relation to the seat and the inlet openings, that under 60 a certain pressure of gas, the valve will remain open sufficiently to allow the desired amount of gas to flow through the extension C' of the valve seat and thence to the burner. If the pressure be increased, the valve will be 65 closed against the seat C, but the grooves or channels H are designed to still allow the proper proportion of gas to flow to the burner, under the increased pressure, so that whether the valve be opened or closed, the light fur- 70 nished from the burner will be an even and steady one, and whatever increase of pressure may take place within the supply pipe, no greater amount of gas will be allowed to flow to the burner.

The upper end of the extension C' is so formed that a screw driver or other device may be applied to it, and it may thus be raised or lowered in the extension E into which it is screwed, and thus the distance between it and 80 the valve when the latter is in its normal position, may be varied to suit the more or less quantity of light required.

By this construction each burner may be regulated to suit the pressure at that particu- 85 lar point, or the requirements of the case, by adjusting the valve seat C, after which the burner F is screwed on to the upper end of the case, and the whole is in readiness for use.

Any future adjustment is made by first re- 90 moving the burner and adjusting the valve seat as previously described.

Having thus described my invention, what I claim as new, and desire to secure by Letters Patent, is—

1. An independent gas burner regulator, consisting of a closed casing having its lower end secured to the gas supply pipe, and a burner secured to the upper end, a valve seat of conical form within said casing, having a hollow 100

extension adjustably fitted to the top of the casing, and a valve of conical form having a guiding stem adapted to enter said extension, said valve seat having grooves formed in its 5 face extending from the lower edge to the apex and communicating with the hollow extension.

2. In a gas burner regulator, the combination, with the gas supply pipe, the burner and 10 the chamber between said pipe and burner, of a conical valve seat and conical valve adapted to close against the same, said valve

seat having grooves or passages in its inclined walls connecting at one end with the chamber and at the upper end with a hollow 15 extension from the valve seat, and said valve having a stem adapted to enter said extension and guide the valve.

In witness whereof I have hereunto set my hand.

JOSEPH KRAKER.
